(57) **CLAIM**

The ornamental design for an oscillating wand sprinkler, as shown and described.

DESCRIPTION

FIG. 1 is an isometric view of an oscillating wand sprinkler showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is an isometric view thereof, shown in an alternate position;

FIG. 9 is a front view of the embodiment of FIG. 8;

FIG. 10 is a rear view of the embodiment of FIG. 8;

FIG. 11 is a left view of the embodiment of FIG. 8;

FIG. 12 is a right view of the embodiment of FIG. 8;

FIG. 13 is a top view of the embodiment of FIG. 8; and,

FIG. 14 is a bottom view of the embodiment of FIG. 8.

The structure shown in dash lines is for illustrative purposes only and forms no part of the claimed design.

1 Claim, 8 Drawing Sheets
